UNITED STATES PATENT OFFICE.

AUGUST HEINE, OF SILVER CREEK, NEW YORK.

CENTRIFUGAL FLOUR-BOLT.

SPECIFICATION forming part of Letters Patent No. 299,784, dated June 3, 1884.

Application filed December 10, 1883. (No model.)

2 all whom it may concern:

Be it known that I, AUGUST HEINE, of Silver Creek, in the county of Chautauqua and State of New York, have invented a new and 5 useful Improvement in Centrifugal Flour-Bolts, of which the following is a specification.

This invention relates to certain improvements in that class of flour-bolts which are provided with a rotating bolting-cylinder and 10 beaters which rotate in the cylinder, and whereby the material is brought in contact with all parts of the bolting-surface.

The object of this invention is the improvement of the operation of this class of machines; 15 and my invention consists, to that end, in the improvements which will be hereinafter fully described and specifically claimed.

In the accompanying drawings, consisting of two sheets, Figure 1 is a longitudinal sectional 20 elevation of a machine provided with my improvements. Fig. 2 is a fragmentary vertical cross-section thereof. Fig. 3 is a side elevation, on an enlarged scale, of the lower conveyer-bearing. Fig. 4 is a vertical section on line x of Fig. 3. Fig. 5 is a horizontal section on 25 line y of Fig. 3. Fig. 6 is a cross-section, on an enlarged scale, of the clothing applied to the bolting-cylinder. Fig. 7 is an enlarged cross-section of the stretching device whereby 30 the longitudinal edges of the clothing are connected. Fig. 8 is a similar view of the auxiliary stretching device applied to the clothing. Fig. 9 is a fragmentary plan view of the last-named stretching device.

35 Like letters of reference denote like parts in the several figures.

A represents the frame of the machine, and A' the inclosing-casing secured thereto.

B represents the bolting-cylinder, arranged 40 within the casing A', and C represents the rotating beaters arranged within the cylinder B.

D represents a preliminary separator arranged 45 within the casing A' lengthwise above the bolting-cylinder B, and consisting of a series of spiral brushes, d , mounted upon a drum, d' , and rotating in a perforated trough, d^2 .

e represents the feed-spout, through which 50 the material to be bolted is introduced into the preliminary separator D, and e' is the discharge-spout through which the coarse material which has not passed through the perforations of the trough d^2 is discharged from the

preliminary separator. The drum d' and the brushes d secured thereto are made tapering from the feed end to the discharge end of the 55 preliminary separator, and the perforated trough d^2 is tapered correspondingly, so that the perforated surface of the trough gradually decreases in the same measure as the bulk of the material decreases by the removal of the 60 fine material which has been bolted through the perforations of the trough. The trough d^2 is so clothed that the fine material which is required to be bolted in the cylinder B passes through the perforations of the trough, while 65 the coarse impurities—dough-balls, nails, stones, &c.—are retained in the trough and finally discharged through the spout e . The mesh of the trough is preferably made progressively finer from its feed end toward its 70 discharge end, in order to expedite the separation at the feed end and prevent coarse particles from being brushed through the trough near the discharge end. The drum d' is made lengthwise adjustable with its shaft by means 75 of set-screws or adjustable collars, whereby the brushes can be adjusted to and from the surface of the perforated trough, as may be necessary.

E represents a screw-conveyer arranged 80 lengthwise underneath the trough d^2 , and adapted to collect the fine material which has passed through the perforations of the trough and conduct the same to the spout f , whereby it is delivered into the head of the bolting- 85 cylinder B.

g represents a shaft arranged axially in the bolting-cylinder B, and G represents the spiders or arms whereby the beaters C are secured to the shaft g in a well-known manner. 90 The beaters C are arranged lengthwise in the cylinder B, and extend from the head thereof toward a point at a greater or less distance in front of the tail end of the cylinder, so as to leave at the tail end of the cylinder a bolting 95 chamber or space, H, which is not provided with any beaters, and in which the bolting of the material is effected merely by the operation of sifting.

h represents the central discharge-opening, 100 through which the tailings are delivered into the discharge-spout I.

J represents an annular head or disk surrounding the shaft g in front of the opening h ,

and extending nearly to the bolting-surface, so as to leave an annular opening, *j*, through which the tailings pass from the bolting-surface into the space behind the disk *J*. The latter is provided on its outer or rear side with radial ribs *j'* in a well-known manner, whereby the tailings are lifted and delivered into the discharge-opening *h*. The disk *J* prevents the light floating material which moves along the axis of the bolting-cylinder from passing directly out of the bolting-cylinder through the central discharge-opening, *h*, and compels this light material to pass toward the bolting-surface before it can escape from the bolting-cylinder. This light material contains valuable particles which descend by gravity in the chamber *H*, and are bolted out on the tail portion of the bolting-cylinder, which is not provided with any beaters, and the specky particles or light impurities contained in this light floating material are therefore not forced through the bolting-surface, but are tailed off. While the head *J* is very effective in effecting the separation of the valuable particles contained in the light material, it may be reduced in size or omitted, when the same result will be attained, but in a less degree.

K, *K'* represent two screw-conveyers arranged lengthwise underneath the bolting-cylinder *B*, and provided with draw-off slides, whereby different grades of the bolted material can be co-mingled or separately discharged, as may be desired.

l represents a pinion mounted on the tail end 35 of the shaft *g*, and gearing into a wheel, *L*, which is secured to a counter-shaft, *l'*.

m is a sprocket-wheel secured to the counter-shaft *l'*, and connected by a chain belt, *m'*, with a similar wheel, *M*, mounted on the shaft 40 *m'* of the lower conveyer, *K'*. The end of the shaft *m'* adjacent to the chain belt *m'* is supported in a vertically-adjustable box or bearing, *N*, which is fitted in dovetail guides *n*, formed on the outer or face side of a standard, *O*, which carries at its upper end a bearing, *O'*, in which the shaft of the upper conveyer, *K*, is supported. The bearing *N* is adjusted by set-screws *p*, which tend to hold the bearing *N* downwardly, and whereby the chain belt *m'* is 45 readily tightened.

Q represents the clothing or covering of bolting-cloth applied to the outer sides of the ribs or skeleton frame of the bolting-cylinder *B*.

55 *q* represents the strips of ticking or other strong material sewed to the longitudinal edges of the bolting-cloth *Q*, and provided with lacing hooks or eyelets *q'*, around or through which is passed the lacing-cord *q''*, whereby the edges of the bolting-cloth are 60 drawn together and the clothing is stretched on the cylinder.

R represents a longitudinal strip of ticking or other strong cloth sewed between two adjoining strips of bolting-cloth, or upon the bolting-cloth itself, and provided with lac-

ing hooks or eyelets *r*, which are connected by a lacing-cord, *r'*. The strip of ticking *R* is preferably arranged diametrically opposite the point at which the two longitudinal edges of 70 the clothing are secured together; but, if preferred, two or more of these intermediate strips, *R*, may be employed. In applying the clothing to the frame of the cylinder *B*, the lacing-cord *r'* is loosened, so that in tightening the cord *q''* the strip of ticking *R* is fully stretched. If the clothing should afterward become loose or baggy, and the strips of ticking *qq* have been drawn so closely together that the cloth cannot be further stretched by tightening the cord *q''*, the auxiliary stretching device is resorted to, and the cloth is further stretched by tightening the cord *r'*. The auxiliary stretching device may also be resorted to when the cloth cannot be uniformly stretched 85 by the device which is applied to the longitudinal edges of the clothing.

I claim as my invention—

1. The combination, with a bolting-cylinder, of a preliminary separator composed of 90 a tapering perforated trough and a tapering brush made lengthwise adjustable in said trough, substantially as described.

2. The combination, with a bolting-cylinder, of a preliminary separator composed of 95 a tapering brush and a tapering perforated trough decreasing in area toward its discharge end, substantially as described.

3. The combination, with a bolting-cylinder, of rotating beaters arranged in the head 100 portion of the cylinder only, leaving a sifting chamber or space near the tail end of the cylinder, and a head or deflector surrounding the axis of the bolting-cylinder at its tail end, whereby the floating material is compelled to 105 pass toward the bolting-surface in said sifting-chamber before escaping from the bolting-cylinder, substantially as described.

4. The combination, with a bolting-cylinder, of rotating beaters arranged in the head 110 portion of the cylinder only, leaving a sifting chamber or space near the tail end of the cylinder, in which the valuable particles contained in the floating material are separated from the light refuse by gravity and sifted 115 out, and a central discharge through which the tailings escape from the bolting-cylinder, substantially as described.

5. The combination, with a bolting-cylinder, of rotating beaters arranged in the head 120 portion of the cylinder only, leaving a sifting chamber, *H*, near the tail end of the cylinder, a central discharge, *h*, for the tailings, and a head or disk, *J*, whereby the floating material is compelled to pass toward the bolting-surface before it passes through the discharge-opening *h*, substantially as described.

6. The combination, with the conveyers *K*, *K'*, chain belt *m'*, and wheel *M*, of the standards *O*, provided with fixed bearings *O'* for 130 one of the conveyer-shafts, vertical guides *n*, set-screw *p*, and the adjustable bearings *N* for

the other conveyer-shaft, substantially as described.

7. A clothing for bolting-reels, composed of a bolting-cloth, Q, having longitudinal edge strips, a stretching device connecting said strips, and an auxiliary intermediate stretching device arranged lengthwise on the clothing, substantially as set forth.

8. A clothing for bolting-reels, composed of a bolting-cloth, Q, longitudinal edge strips, q, of strong material, a lacing connecting said strips, an intermediate longitudinal strip, R, of strong material, and a lacing applied to said strip, substantially as set forth.

9. The combination, with the reel-frame, of 15 a clothing composed of a bolting-cloth, Q, having longitudinal edge strips, a stretching device connecting said strips, and an auxiliary intermediate stretching device arranged lengthwise on the clothing, substantially as 20 set forth.

In testimony whereof I have hereinunto set my hand this 30th day of November, 1883.

AUG. HEINE.

In presence of—

EDWARD WILHELM,
F. L. BROWNE.
